UNITED STATES PATENT OFFICE.

WILLIAM E. STEVENS, OF NEW HAVEN, CONNECTICUT, ASSIGNOR TO SARGENT & COMPANY, OF NEW HAVEN, CONNECTICUT, A CORPORATION OF CONNECTICUT.

DESIGN FOR CASKET-TRIMMING.

No. 38,389.

Specification for Design.

Patented Dec. 25, 1906.

Application filed November 14, 1906. Serial No. 343,463. Term of patent 14 years.

To all whom it may concern:

Be it known that I, WILLIAM E. STEVENS, of the city and county of New Haven and State of Connecticut, have invented a new, original, and ornamental Design in a Casket-Trimming, of which the following is a specification, when taken in connection with the accompanying drawings, which form a part thereof, and in which—

Figure 1 represents a front elevation of a

casket-trimming embodying my new, original, and ornamental design; and Fig. 2 represents an end view of the same.

What I claim is—

The ornamental design for a casket-trimming, as shown.

WM. E. STEVENS.
